CLAIM

The ornamental design for a wrench tool for sports equipment, as shown and described.

DESCRIPTION

FIG. 1 is a top perspective view of a wrench tool for sports equipment;

FIG. 2 is a bottom perspective view of the wrench tool of FIG. 1;

FIG. 3 is a front view of the wrench tool of FIG. 1;

FIG. 4 is a rear view of the wrench tool of FIG. 1;

FIG. 5 is a top view of the wrench tool of FIG. 1;

FIG. 6 is a bottom view of the wrench tool of FIG. 1;

FIG. 7 is a right view of the wrench tool of FIG. 1; and,

FIG. 8 is a left view of the wrench tool of FIG. 1.

The broken lines shown in one or more of the figures are for illustrative purposes only and form no part of the claimed design.
